(57) **CLAIM**

The ornamental design for a spraying device for bottle, as shown and described.

DESCRIPTION

FIG. 1 is an isometric view of the spraying device for bottle embodying our new design;

FIG. 2 is a right side view thereof;

FIG. 3 is a front view thereof;

FIG. 4 is a top view thereof;

FIG. 5 is a bottom view thereof;

FIG. 6 is a back view thereof;

FIG. 7 is a left side view thereof.

FIG. 8 is an isometric view of the spraying device for bottle embodying our new design, shown in an alternate environment;

FIG. 9 is a right side view thereof;

FIG. 10 is a front view thereof;

FIG. 11 is a top view thereof;

FIG. 12 is a bottom view thereof;

FIG. 13 is a back view thereof; and,

FIG. 14 is a left side view thereof.

The broken lines shown in the drawings depict environmental subject matter only and form no part of the claimed design.
